REMOTE-CONTROL MECHANISM

Andrew McMillan, Milwaukee, Wis., assignor to
 Chain Belt Company, Milwaukee, Wis., a corporation of Wisconsin

Application February 26, 1946, Serial No. 650,189

3 Claims. (Cl. 74—471)

1

The invention relates to remote control mechanism, and has for its principal object the provision of a simple and relatively inexpensive apparatus of the Bowden wire type by means of which a plurality of levers, handles or similar control elements may be actuated in sequence through successive movements of a single actuating member.

The invention is susceptible of various applications, of which the remote control of internal combustion engines may be cited as typical. For example, it is common practice to control the starting and stopping of a Diesel motor by means of a lever controlling a fuel supply valve, and to vary the speed of the engine between idling and maximum by manipulation of a second lever. The mechanism of the present invention provides means whereby sequential operation of two such elements may be effected through manipulation of a single actuating member, to the end that the fuel valve lever may be first actuated to open the valve to start the engine, subsequent to which the speed control lever may be advanced and retarded to vary the speed as desired, while the fuel valve lever remains in its open position. Conversely, in stopping the engine the speed regulating lever will be first moved to idling position, after which the fuel valve lever will be shifted to close the valve.

Although various other uses will readily suggest themselves, for purposes of disclosure of the principles of the invention it will be described in connection with the actuation of such engine controlling levers, with the full scope of the invention being defined in the appended claims.

In the accompanying drawing forming a part of this specification:

Figure 1 is an elevational view, partly diagrammatic and in section, illustrating the several parts in the positions they occupy when the motor is stopped;

Fig. 2 is a similar view illustrating the positions of the parts when the motor is running at idling speed; and

Fig. 3 is a view showing the positions assumed when the motor is running at maximum speed.

In the said drawing 11 indicates an oscillatory lever or control element by means of which the fuel supply valve (not shown) may be opened and closed whereby to start and stop the engine, while 12 indicates an oscillatory lever or control element by means of which the speed regulating device (also not shown) may be actuated to secure variations in the engine speed between idling and maximum. Suitable stops 13 and 14

may be provided to limit the movements of the lever 11, while similar stops 15 and 16 limit the movements of the lever 12, which is biased to the idling position against stop 15 as by a spring 17.

The control element 11 is connected by a link 18 to one end of a rock lever 19, the other end of which has attached to it, as by a clip 20, an end portion of the spirally wound sheath 21 of a Bowden wire or like flexible power transmitter 22. An end portion of this wire protrudes somewhat from the end of the sheath, as indicated in Fig. 1, and is attached to the control element 12 by an appropriate connector 23. The wire and its sheath extend to a remote operating station, where the other end of the wire is connected by a suitable connector 24 to an actuating member, such for example as a lever 25, by means of which longitudinal movement may be imparted to the wire in either direction. The sheath 21 is anchored against movement at appropriate points throughout its length, as by clips 26 and 27, so that the wire will slide within it.

The parts are so proportioned and assembled that when they are in the "stop" positions of Fig. 1, that portion of the cable structure intermediate the clips 20 and 26 is displaced transversely of the structure axis to a bowed or arcuate condition, as indicated at 28. This is due to the fact that the portion of the sheath 21 between the clips 20 and 26 is of a length substantially equal to the distance between such clips when the lever 19 is in the position of Figs. 2 and 3, while the length of the wire 22 is somewhat greater than the distance between the connectors 23 and 24 when these are in the positions of Fig. 1. As a result, since counterclockwise movement of the control element 12 beyond its "idle" position is prevented by the abutment or stop 15, the force exerted on the wire through lever 25 as the latter is moved from its "idle" to its "stop" position causes the portion of the cable structure intermediate the clips 20 and 26 to assume the arcuate or bowed condition indicated in Fig. 1. Since the sheath is firmly anchored against movement by the clip 26 while the lever 19 and its clip 20 are movable, this bowing produces a longitudinal displacement of the sheath end and clip 20 which causes the lever 19 to assume the Fig. 1 position.

The parts will remain in their Fig. 1 positions so long as the actuating lever 25 is retained in its "stop" position. However, if the said lever be moved to the "idle" position, as shown in Fig. 2, it will tension the wire 22 and tend to draw

it through the sheath from left to right, as viewed in the drawings. The biasing spring 17 is sufficiently strong to prevent movement of the speed control lever 12 away from its stop 15 during this portion of the movement of actuating lever 25, and since the control element 11 is unbiased in either direction, it results that the portion of the cable 22 between the clips 20 and 26 is straightened and the bow 28 eliminated. With the sheath 21 firmly anchored against movement at 26, this straightening of the cable structure causes the left hand end of the sheath to be forced toward the left, thus rocking the lever 19 in a counterclockwise direction and, through link 18, shifting the control element 11 to its "run" position of Fig. 2. The motor may now be started and will run at idling speed, since the speed control element 12 is still in its "idle" position.

If it be desired to increase the speed of the motor, further movement of the actuating lever 25 toward or to its "maximum" position of Fig. 3 will overcome the force of the spring 17 and draw the wire 22 through the sheath 21, thus moving the speed control element 12 toward or to its "maximum" position, shown in said figure. A quadrant or other appropriate detent 29 may be associated with the lever 25, whereby the parts may be retained in any desired position.

Obviously, release of the lever 25 whereby it may be returned to its "idle" position will permit the cable 22 to be drawn through the sheath 21 by the spring 17 and thus restore the speed control element 12 to its Fig. 2 position against the abutment 15. If movement of the lever 25 be continued to its "stop" position, since the abutment 15 will prevent further movement of control element 12, the push now imposed upon the wire will again produce the bow or arc 28 in the cable structure, thereby restoring the parts 19, 18 and 11 to their Fig. 1 positions and stopping the motor.

The rock lever 19 and link are merely direction reversing connections which enable the control element 11 to be moved in the same directions as the element 12, and obviously in any case where it may be necessary or desirable that the elements move in opposite directions the said connections 19 and 19 may be omitted and the element 11 connected directly to the sheath end by the clip 20.

In any application of the invention which may call for the element 12 being shifted toward the right ahead of movement of the element 11 and toward the left subsequent thereto, the biasing spring 17 may be applied to the last named element instead of to the element 12, which will defer straightening of the bowed portion 28 of the cable structure until the element 12 has been brought into engagement with stop 16.

What is claimed is:

1. In remote control mechanism for engines, the combination of a pair of reversible control levers operable in sequence to govern respectively the starting and stopping, and the rate of speed, of the engine; a flexible cable structure comprising a longitudinally movable cable connected to one of said levers for actuation thereof, and a tubular sheath slidably housing said cable and having a portion connected with the other lever for actuating the same; means spaced from said sheath connection for anchoring the sheath against longitudinal movement, the cable structure intermediate said anchor means and sheath connection being free for transverse flexing move-

ments whereby to cause displacement of said connection longitudinally of the cable structure; means for temporarily preventing movement of one of the levers in one direction, whereby force applied to cable in one direction longitudinally thereof will produce transverse flexing of said free portion of the cable structure in one direction with consequent longitudinal displacement of the sheath connection and movement of the sheath-actuated lever in sequence with movement of the cable-actuated lever; and means for positively limiting movement of one of the levers, whereby force applied to the cable in the opposite longitudinal direction will produce reverse transverse flexing of the free portion of the cable structure and sequential movements of the levers in their reverse direction.

2. In remote control mechanism for engines, the combination of a pair of reversible control levers operable in sequence to govern the starting and stopping, and the rate of speed of the engine, respectively; a flexible push-pull cable structure comprising a longitudinally movable cable connected to one of said levers for actuation thereof, and a tubular sheath slidably housing said cable and having a portion connected with the other lever for actuating the same; means spaced from said sheath connection for anchoring the sheath against longitudinal movement, the cable structure intermediate said anchor means and sheath connection being free for transverse flexing movements between an arcuate and a substantially rectilinear condition whereby to cause displacement of said sheath connection longitudinally of the cable structure; means for yieldably restraining the cable-actuated lever against pull on the cable whereby such pull will initially produce transverse flexing of said free portion of the cable structure from its arcuate to its rectilinear condition with consequent longitudinal displacement of the sheath connection and movement of the sheath-actuated lever in advance of movement of the cable-actuated lever; and stop means for limiting movement of the cable-actuated lever resulting from push on the cable, whereby such push will produce transverse flexing of the free portion of the cable structure back to its arcuate position with resultant reverse movement of the sheath-actuated lever subsequent to reverse movement of the cable-actuated lever.

3. In remote control mechanism for engines, the combination of a pair of control levers operable in sequence to govern the starting and stopping, and the speed of the engine, respectively; a flexible cable structure comprising a longitudinally movable cable connected to the speed control lever, and a tubular sheath slidably housing said cable and having a portion connected to the starting lever; means spaced from said last named connection for anchoring the sheath against longitudinal movement, the cable structure intermediate said anchor means and sheath connection being free for transverse flexing movements whereby to cause displacement of the sheath connection longitudinally of the cable structure; a remotely located operating lever connected to said cable for moving the same in either direction at will; resilient means for initially restraining said speed control lever against movement by the cable in one direction, whereby such cable movement will first produce transverse flexing of said free portion of the cable structure with resultant longitudinal movement of the sheath connection and shifting of the

starting lever, followed by yielding of said resilient means and shifting of the speed control lever; and stop means engageable by the speed control lever in its low speed position, for causing reverse movement of the cable to transversely flex the free portion of the cable structure after such lever reaches said position, with resultant sequential movement of the other lever to its stop position.
